THREADED ELECTRIC FUSE

Mariano Ahedo Garibay, San Pedro de los Pinos,
Mexico City, MexicoApplication November 8, 1946, Serial No. 708,549
In Mexico November 9, 1945

1 Claim. (Cl. 200—130)

1

This invention relates to a threaded electric fuse, to be used in electric circuits as a protection against overloads, excessive voltages and the general purposes of a fuse of its kind.

An object of this invention is to provide a threaded electric fuse, specially designed for its use in home electrical installations, substituting with advantage all types of threaded electric fuses commonly used.

Another object of this invention is to provide a fuse of very simple design and construction using a minimum of materials, to obtain a low cost electric fuse, which may be replaced as many times as necessary, and which may be purchased in sufficient numbers, to avoid the dangerous custom of substituting coins, tin foil and other unsafe materials, placed in the fuse sockets for fuses.

A further object of this invention is to provide a threaded electric fuse, which makes impossible the substitution of the fusible material, which has been designed to provide the necessary protection against overloads, with any temporary and unsafe replacement, such as copper wires, or any other material not adequate for the particular electric circuit.

A further object of this invention is to provide a threaded electric fuse, which makes possible the quick examination of the conditions of the fusible material, for its replacement, if necessary.

With the above and other objects in view, my invention consists in the arrangement, combination and details of construction disclosed in the drawings and specification, and then more particularly pointed out in the appended claim.

In the drawing:

Figure 1 is a perspective view of the electric fuse, showing the construction of the flat supporting body.

Figure 2 is a bottom plan view of the fuse threaded in the fuse socket.

Figure 3 is a sectional view taken substantially on the line 3—3 of Figure 1.

Referring to the drawing, numeral 10 generally designates a flat supporting body, made of any adequate insulating material, preferably plastic, forming a thin elongated body, with an upper portion provided with small indentations 11, to give a better support when screwing said threaded fuse in the corresponding socket of the fuse box.

This body 10 is provided in its lateral portions with a threaded section 12, corresponding to the threads of the socket 13, in which these lateral portions engage. Lateral portions 12, may be

2

thicker than the supporting body 10, as to provide a more efficient contact and support to the walls of the socket 14.

Body 10, at one of its lateral portions is provided with a perforation 15, which extends from the middle lateral portion to the middle lower portion of said body 10.

The fuse material, usually a cylindrical body of material which fuses when heated by an excessive voltage or overload in the circuit, is located in perforation 15, so that the projecting ends of said fuse body 16, make contact with the electrodes of the socket where the fuse is threaded.

In order to provide a more efficient electrical contact, these projecting ends of the fuse body 16, are rounded or convenient shaped, to increase their contact surface.

Supporting body 10, is also provided in its middle lateral flat portion, with a window or opening 17, which is transversed by the fuse body 16, providing the means to observe the condition of the fuse, and to allow space for the fusion of said body 16. This window or opening 17, may be covered with a transparent heat insulated thin plate 18, such as mica.

The fuse body 16 may be of the ribbon type with a thinner or narrower portion at its fusing point. In any case this fuse body has rounded ends at the middle lower and lateral portions of the supporting body 10, which may be provided with small metallic sections for a better electric contact with the threaded walls of the socket.

The threaded electric fuse embodied in this invention, replaces and substitutes with advantage, the fuses now used in electrical installations. Due to its extreme simplicity, it greatly reduces the manufacturing costs. The construction and design of its lateral walls makes possible its use in standard fuse boxes, and the rounded ends of the fuse body and metallic pieces, assure a positive connection with the electrodes of the socket. Its main opening or window provides a space for the fusion of the material, as well as the means for observing the condition of the fuse, making it impossible to replace the fuse body or repair the fuse.

What I claim is:

A fuse comprising a flat solid body of non-conducting material, correlated notches formed on the opposite side edges of said body constituting segmental threads for said body longitudinally thereof, said body formed with a transverse opening therethrough, a pair of spaced apart transparent panels closing the opposite ends of

said opening, a fusible element carried in said body between the bottom edge thereof and one side edge, a contact member connected to said fusible element on the said bottom edge, a contact member connected to said fusible element along one side edge, said fusible element extending diagonally across said opening between said transparent panels whereby the condition of said fusible element may be readily viewed.
